No. 842,761.

PATENTED JAN. 29, 1907.

T. V. BUCKWALTER.

FISHING REEL.

APPLICATION FILED MAY 9, 1906.

UNITED STATES PATENT OFFICE.

TRACY VERE BUCKWALTER, OF ALTOONA, PENNSYLVANIA.

FISHING-REEL.

No. 842,761.

Specification of Letters Patent.

Patented Jan. 29, 1907.

Application filed May 9, 1906. Serial No. 315,939.

To all whom it may concern:

Be it known that I, TRACY V. BUCKWALTER, a citizen of the United States, and a resident of Altoona, in the county of Blair and State of Pennsylvania, have invented a new and Improved Fishing-Reel, of which the following is a full, clear, and exact description.

This invention relates to fishing-reels, and is especially useful in connection with devices of this class adapted to be attached to fishing-rods.

The object of the invention is to provide a reel of simple and strong construction and which permits the strain in winding the line upon the spool to be exerted in the plane of the longitudinal axis of the rod, and thus obviates a distortion of the same in the hand of the operator.

The invention consists in the construction and combination of parts, to be more fully described hereinafter and particularly set forth in the claims.

Reference is to be had to the accompanying drawings, forming a part of this specification, in which similar characters of reference indicate corresponding parts in all the figures.

Figure 1 is a plan view of my invention as applied to a fishing-rod. Fig. 2 is an elevation of the device, showing a part in cross-section. Fig. 3 is a plan view of the lower portion of the invention. Fig. 4 is a partial cross-section on the line 4-4 of Fig. 2. Fig. 5 is an elevation of a modified form of the device, showing a part in cross-section; and Fig. 6 is a horizontal section of the modified form.

Referring more particularly to the drawings, I employ a reel-body 1 of the usual form, having a spool 2, pivotally mounted between side plates 3, which are joined by pillars 4. Secured to the lower portion of the reel-body is a base-plate 5, having at an extremity lateral flanges 6, which are attached, by means of screws 7, to extensions 8 of one of the side plates 3. Angle-blocks 9 are attached to the base-plate 5 by means of rivets 10 and are adapted to be secured to the extensions 11 of the other side plate by means of screws 12. The base-plate 5 projects laterally beyond the reel-body and is provided with a hole for a purpose which will appear hereinafter.

I employ a reel cross-plate 13, which is adapted to be mounted upon the reel-seat 14 of a fishing-rod 14 and to be secured thereto by sliding rings 15, which are adapted to be

slipped over the curved ends 16 of the reel cross-plate. Rigidly attached to the reel cross-plate 13, near its center, is an upwardly-projecting and threaded stud 17, which passes through the hole provided therefor in the base-plate 5. I provide a thumb-nut 18, which is adapted to screw onto the stud 17 and secure the base-plate 5 to the cross-plate 13. The cross-plate 13 is provided with ledges 19, which are rigidly mounted thereon by means of rivets 20 on each side of the base-plate 5. The inner edges of the ledges are at an angle with the edge of the base-plate 5 for a purpose to be described hereinafter.

By means of the extension of the base-plate it is possible to mount the reel upon the rod on one side of the longitudinal center line of the same, thus bringing the handle, by means of which the reel is operated, directly over this center line, and when the handle is turned the strain incident to this turning is brought to bear directly downward upon the rod and not to one side of the same, with a consequent tendency to twist the rod in the hand of the user.

It will be understood that in order to have the line wind smoothly upon the spool of the reel the direction of the line should be at an obtuse angle with the axis of the reel. In order to accomplish this, when the reel is offset as described above I attach the same to the rod in such a manner that the axes of the reel and of the rod are at an angle with one another, as most clearly shown in Fig. 1, and the axes of the reel and of the rod will intersect at a point approximately near the first line-guide 21 of the rod. That the reel may be set at any suitable angle with the rod the sides of the ledges 19 of the cross-plate 13 slope outwardly, and, as shown most clearly in Fig. 3, the base-plate may be thus secured to the cross-plate at any desired angle by tightly screwing down the thumb-nut 18.

In order that the reel may be used on the upper side as well as the under side of the rod, it is necessary that the base-plate be set at an angle with the cross-plate in a relatively forward as well as a backward position, according to Fig. 3, which shows the base-plate when the reel is to be used on the upper side of the rod. If it is to be used on the under side of the rod, the reel can be reversed and the base-plate set at an opposite angle, and the sides of the base-plate will then be in contact with those portions of the inner edges

of the stops which slope in the other direction.

In the modified form of the device shown in Figs. 5 and 6 I provide a cross-plate 22, 5 having upwardly-projecting lateral extensions 23, provided with openings to receive extension-rods 24, which are provided at one end with collars 25 and threaded extremities 26. Between the extensions 8 and 11 of the 10 side plates 3 of the reel-body are secured hollow pillars 27, adapted to be secured to the extensions 8 and 11 by means of screws 28 and the threaded extremities 26 of the extension-rods, as shown most clearly in Fig. 6.

15 Having thus described my invention, I claim as new and desire to secure by Letters Patent—

1. In combination with a fishing-rod having a reel-seat, a reel having sides, a base-plate secured to said sides and projecting laterally therebeyond, and means for pivotally attaching said base-plate to said reel-seat.

2. A reel, comprising a body having sides, 25 a base-plate rigidly mounted upon said sides and extending laterally therebeyond, a cross-plate adapted to be removably attached to a fishing-rod, and means for pivotally mounting said base-plate upon said cross-plate.

3. A reel comprising a body having sides, a base-plate rigidly mounted upon said sides and extending laterally therebeyond, a cross-plate adapted to be removably at-

tached to a fishing-rod and having a stud 35 and stops, said cross-plate being adapted to be mounted upon said stud, and means for pivotally securing said base-plate to said cross-plate.

4. A reel comprising a body having sides, 40 a base-plate rigidly mounted upon said sides and extending laterally therebeyond, a cross-plate adapted to be removably attached to a fishing-rod and having ledges transversely of said cross-plate, and means 45 for pivotally securing said base-plate to said cross-plate between said ledges, whereby said ledges are adapted to constitute stops to limit the movement of said base-plate.

5. A reel comprising a body having sides, 50 a base-plate secured to said sides and projecting laterally therebeyond, a cross-plate adapted to be removably attached to a fishing-rod and having transverse ledges constituting stops, and means for pivotally attaching said base-plate to said cross-plate between said ledges, said ledges having inner edges of opposite inclination whereby the edges of said base-plate are in contact with the inner edges of said ledges when the reel 55 is set at an angle with the fishing-rod.

In testimony whereof I have signed my name to this specification in the presence of two subscribing witnesses.

TRACY VERE BUCKWALTER.
